UNITED STATES PATENT OFFICE.

CHARLES E. MASON, OF ATTLEBOROUGH, MASSACHUSETTS.

DESIGN FOR AN ORNAMENT UPON LOCKET-FACES, &c.

SPECIFICATION forming part of Design No. 12,101, dated January 4, 1881.

Application filed November 4, 1880. Term of patent 3½ years.

To all whom it may concern:

Be it known that I, CHARLES E. MASON, of Attleborough, in the county of Bristol and State of Massachusetts, have invented a new and useful Design for Ornament upon the Faces of Lockets and other Articles of Jewelry; and I do hereby declare that the following specification, taken in connection with the accompanying drawing, forming a part of the same, is a full, clear, and exact description thereof.

My design relates to the composition and arrangement of ornament upon the faces of lockets and other articles of jewelry; and it consists of the following features:

The central surface of the face of the article is inclosed by a raised band, A, bordering the interior of which are arranged a series of semi-rings and spheres or hemispheres in groups of three. Outlying and surrounding the band A is a border, B, composed of rings and spheres or hemispheres, the rings being tangent to each other and the spherical portions occupying the centers of said rings.

The whole may be surrounded, if desired, by a bead-border, as shown; but such border

forms no part of the design, and may be omitted or changed in character.

Although, as represented in the drawing, the ornament is arranged upon a surface having the outline of an ellipse, yet said surface may have a rectangular or circular contour, and the ornament be arranged concentric therewith, without changing the character and arrangement of the parts of the design, the essential features of which are a raised band, A, surrounding the central surface of the article, and bordered internally by semi-rings and spheres or hemispheres in groups of three, and an outlying and surrounding border, B, composed of rings and spheres or hemispheres.

Having described my invention, what I claim, and desire to secure by Letters Patent, is—

The design for ornament upon the faces of lockets and other articles of jewelry, substantially as set forth.

CHARLES E. MASON.
